UNITED STATES PATENT OFFICE

LOUIS G. BRADFIELD, OF LOS ANGELES, CALIFORNIA

FOLDING GATE

Application filed April 23, 1929. Serial No. 357,365.

This invention relates to folding gates, a type of structure employed, for example, at the fronts of fruit and vegetable stands. This type of gate is used where it is necessary to close the front of a building and, at the same time, permit of ventilation through the closure means.

Ordinarily in closures of this type, the panels fold against one another and are shiftably mounted on a track so that, when the closure is folded, the panels obstruct the opening at the extreme ends thereof, and a very important object of this invention is to make provision for swinging the panels to the sides of the opening, for example, along the rear face of the wall in which is the opening that the gate is provided to close.

Another object is simplicity and inexpensiveness of construction.

20 Further objects and advantages will appear in the subjoined detailed description.

The accompanying drawings illustrate the invention.

Figure 1 is a rear elevation of a folding gate constructed in accordance with the provisions of this invention, one section of the gate being shown in closed position and the other with its panels folded together.

Figure 2 is an enlarged sectional detail on the irregular line indicated by 2-2, Figure 1.

Figure 3 is an enlarged sectional detail on the line indicated by 3-3, Figure 1.

Figure 4 is an enlarged fragmental view of the construction shown in the upper right hand portion of Figure 1, two different positions of the latch being shown in solid and broken lines.

Figure 5 is a plan view of Figure 4, partly in section, on the line indicated by 5-5. Broken lines indicate some of the parts in the positions they occupy when the pivoted track section is swung into a position at right angles to the plane of the opening.

Figure 6 is a fragmental vertical section on the line indicated by 6-6, Figure 4.

Figure 7 is an enlarged fragmental view of the construction in the lower right hand portion of Figure 1.

50 Figure 8 is a plan view, partly in section,

from the line indicated by 8-8, Figure 7, broken lines indicating some of the parts in the same positions as the same parts are indicated by broken lines in Figure 5.

A wall is indicated at A and said wall is provided with an opening B which is to be closed by the invention that will now be described.

Mounted along the upper margin of the opening B and secured to the wall A by brackets 11 is a rail comprising a stationary intermediate section 12 and pivotally mounted end sections 13. The closure means is formed in sections, two in this instance, and each section comprises a number of hingedly connected panels 14. These panels may be solid but, in this instance, are illustrated constructed of frames 141 and secured thereto wire netting 142. The hinges 15 connect the panels in pairs and some of the hinges are placed on the front face of the panels and others on the rear face so that the panels will fold one against another, in the manner illustrated at the right hand of Figure 1. The hinges 15 are secured to the frames 141.

The outermost panel 14 at each end of the closure is hinged at 16 to a pivoted standard 17, there being a pivot 18 projecting from the upper end of each standard and a pivot 19 projecting from the lower end of each standard.

Alternate panels 14 are shiftably supported on the track by rollers 20, said rollers being arranged in pairs to run on the inwardly turned flanges 21 of the rail. Connecting the rollers 20 of each pair is an axle 22 and on each axle is a sleeve 23. Projecting downwardly from each sleeve is a hanger 24 and said hangers are connected to the respective panels in such position as to permit the panels to be in either open or closed position when the rollers 20 are engaged with the rail. The hangers 24 are swiveled at 241 in the frames 141.

The pivots 18 rotate in bearings 25 secured to the wall A and the pivots 19 project into sockets 26 that are embedded in the floor of the building provided with the closure. Each of the pivots 19 is provided with an anti-friction bearing 27.

Alternate panels 14 are provided with pins 28 fixed in the frames 141 and slidably engaging in a bottom rail, said bottom rail comprising two pairs of hingedly connected sections 29, 30, the sections 30 being secured to the lower ends of the standards 17 and the sections 29 being pivoted or hinged at 31 to the sections 30, thus enabling the rail sections 29 to be raised into vertical positions when the panels are in their folded positions, as indicated at the right hand of Figure 1. The pins 28 engage in the longitudinal channels 32 in the bottom rails. The pins 28 are on those panels that are suspended from the rollers 20.

At the hinged panel joints that, when the panels are being folded, are thrust away from the top and bottom rails, the frames of alternate panels are provided at their upper and lower ends with vertically shiftable pins 33 which, when the panels are in the unfolded positions, are adapted to engage in the appropriate channel 32, if it be a bottom pin, or in the channel 331 in the upper rail, if it be a top pin, so that the panels will be releasably held against folding.

Each of the pins 33 passes through a bracket 34 secured to the associated frame 141 and each of the pins 33 is provided with a shoulder 35 between which and one end of the bracket 34 and surrounding the pin is a coil spring 36 which yieldingly urges the pin 33 toward the upper or lower rail, as the case may be, to hold it in either the channel 32 or the channel 331. The upper and lower pins 33 are connected in pairs to a release line 37 which may be a chain or other suitable flexible member. The release lines 37 pass upwardly along the frames 141 and are of sufficient length to permit the springs 36 to hold the pins 33 in their latching positions. To release said pins the operator will simply grasp the release line at any desired point and pull the same away from the frame.

When it is desired to have the panels in their unfolded or closed positions, the rail sections 12, 13 are aligned and it is desirable to releasably hold them in such aligned position so as to insure against the rollers 20 running off of the ends of the rail sections 12, 13, and this is effected by suitable latches, the details of which are better illustrated in Figures 4 and 5. Since these latches are of like construction, it will be necessary to describe only one of them in detail, as follows: the track section 12 is provided with a laterally projecting lug or lugs 38, each of which is provided with a slot 39. Releasably engaging in the slots 39 is the inner end of a pivoted arm 40, the pivot being indicated at 41 and being secured in the rail section 13. To the outer end of the arm 40, which thus constitutes a latch member, is pivoted at 42 an operating member 43 in the form of a rod

which passes through a guide 44 secured to the standard 17.

The slots 39 open downwardly through the lower edge of the lugs 38 and, accordingly, the weight of the rod 43, in this instance, is depended upon for holding the latch member 40 in latching position, as indicated in solid lines in Figure 4. To unlatch the latch member 40, the operator will lift the rod 43, thus depressing the inner end of the latch member, as indicated in broken lines in Figure 4, thereby moving said inner end out of the slots 39.

Preferably, the joints 45 between the rail sections 12, 13 are aslant, like mitre joints, the slant being so that the ends of the sections 12 function as stops for limiting movement of the sections 13 when they are being swung into position to align them with the section 12.

The foregoing will make clear the construction and operation of the invention and, briefly stated, the operation is as follows: to open the unfolded panels illustrated on the left of Figure 1, the operator will pull on the release lines 37 to retract the pins 33 and he will then push the innermost panel 14 toward the adjacent side of the opening, thus causing the panels to fold one against another, the rollers 20 running in the rail section 12 and then from said rail section into the rail section 13. This places the panels close to and in parallelism with the adjacent end wall of the opening.

The operator next swings the bottom rail section 29 upwardly into the vertical position as shown at the right in Figure 1 and said section 29 is secured in this position in any suitable manner. In this instance this is effected by a hook 46 which is secured to one of the frames 141 and which is hooked over a pin 47 that projects from the rail section 29.

The operator next lifts the rod 43 so as to retract the latch member 40, thus to release the rail section 13 from the rail section 12. He then pushes on the folded panels in a direction to cause them to swing into a position at a right angle to the adjacent end wall of the opening or, in other words, to a position parallel to the plane of said opening and parallel to the plane of the inner face of the wall A, as clearly shown in broken lines in Figures 5 and 8 of the drawings.

To unfold the panels into the closed position, in Figure 1, the operator will reverse the above described operations.

It will be noted that the rail sections 29, when in lowered positions, are adjustably supported by nuts 48 which rest on the upper ends of tubular sockets 49 mounted in the floor. The nuts 48 are screwed onto studs 50 which project downwardly from the rail sections 29, said studs projecting loosely into the sockets 49 when the rails are lowered. Thus any suitable adjustment of the rail sections 29

relative to the lower edges of the panels may be secured by turning the nuts 48.

At the lower end of those panels 14 that are provided with the latch pins 33, are stops in the form of downwardly projecting lugs 51, said lugs projecting below the lower edges of the panels a sufficient distance to engage one side of the rail section 29. The lugs 51 are on that face of the panels that moves inwardly from the rail section 29, assuming that the invention is mounted on the inner face of the wall A, which is the usual position for it, though it is to be understood that it could be mounted, just as readily, on the outer face of said wall.

It is to be understood that the term "gate" employed herein defines a door as well as a gate and that the panels need not necessarily be of reticulated or openwork construction.

20 I claim:

1. A folding gate comprising a rail of sectional construction, the sections being separate and one of the rail sections being movably mounted, and movably connected panels 25 slidably and pivotally suspended from the rail and foldable alongside of one another.

2. A folding gate comprising a rail of sectional construction, the sections being separate and one of said sections being movably 30 mounted, hingedly connected panels, and means slidably and pivotally suspending alternate panels from the rail.

3. A folding gate comprising a rail of sectional construction, the sections being separate and one of said sections being movably mounted, hingedly connected panels, means 35 slidably and pivotally suspending alternate panels from the rail, and a means on each of the other panels to releasably and slidably engage the rail.

4. A folding gate comprising a rail of sectional construction, the sections being separate and one of said sections being pivoted to swing horizontally away from the adjacent 45 rail section, hingedly connected panels, and means slidably and pivotally suspending alternate panels from the rail.

5. A folding gate comprising a rail of sectional construction, the sections being separate and one of said sections being movably 50 mounted, hingedly connected panels, means slidably and pivotally suspending alternate panels from the rail, and means to latch the rail sections in alignment.

55 6. A folding gate comprising a rail of sectional construction, the sections being separate and one of said sections being pivoted to swing horizontally away from the adjacent rail section, hingedly connected panels, 60 means slidably and pivotally suspending alternate panels from the rail, and means to latch the rail sections in alignment.

65 7. A folding gate comprising a top rail of sectional construction, the sections being separate and one of the sections being pivoted

to swing horizontally away from the adjacent rail section, hingedly connected panels, means slidably and pivotally suspending alternate panels from the rail, a sectional bottom rail, one of the bottom rail sections pivoted to swing horizontally and the other pivoted to the first mentioned bottom rail section to swing into vertical position, a means on the lower end of each of said intermediate panels slidably engaging in the bottom rail, and means to latch said other bottom rail section to one of the panels.

8. A folding gate comprising a top rail of sectional construction, the sections being separate and one of the sections being pivoted to swing horizontally away from the adjacent rail section, means to latch the rail sections in alignment, hingedly connected panels, means slidably and pivotally suspending alternate panels from the rail, a sectional bottom rail, one of the bottom rail sections pivoted to swing horizontally, the other section of the bottom rail pivoted to the first mentioned bottom rail section to swing into vertical position, a means on the lower end of each of said intermediate panels slidably engaging in the bottom rail, and a means to latch said other bottom rail section to one of the panels.

9. A folding gate comprising a top rail of sectional construction, the sections being separate and one of said sections being pivoted to swing horizontally away from the adjacent rail section, hingedly connected panels, means slidably and pivotally suspending alternate panels from the rail, a sectional bottom rail, one of the bottom rail sections pivoted to swing horizontally, the other bottom rail section being pivoted to the first mentioned bottom rail section to swing into vertical position, a means on the lower end of each of said alternate panels slidably engaging in the bottom rail, a means on the lower end of each of said other panels releasably engaging in the bottom rail, and a means to latch said other bottom rail section to one of the panels.

10. A folding gate comprising a pivotally mounted standard, hingedly connected panels, one of the panels being hinged to the standard, a rail of sectional construction, the sections being separate and one of said sections being secured to the standard, and a means slidably and pivotally suspending alternate panels from the rail.

11. A folding gate comprising a pivotally mounted standard, hingedly connected panels, one of the panels being hinged to the standard, a top rail of sectional construction, the sections being separate and one of said sections being secured to the standard, a means slidably and pivotally suspending alternate panels from the rail, a sectional bottom rail, one of the bottom rail sections being secured to the standard and the other bot-

tom rail section being pivoted to the first mentioned bottom rail section to swing into vertical position, and a means to latch said other bottom rail section when in vertical position to one of the panels.

5 Signed at Los Angeles, California, this 12th day of April, 1929.

LOUIS G. BRADFIELD.
